ELECTRIC CONTACT MEMBER

Henry T. Bussmann, St. Louis, Mo.

Application December 16, 1936, Serial No. 116,090

7 Claims. (Cl. 200—114)

My invention relates to electrical contact members adapted to make disengageable contact with a cooperating contact member whereby an electric circuit may be broken under load, and is particularly applicable to contact members mounted in, on or in close association with electric insulating material commonly referred to as "molded insulation", containing an organic constituent, such as "Bakelite".

10 An object of my invention is to provide a contact member which will lessen the duration of an arc which may be produced at the contact member when it is used to open a circuit when carrying current.

15 Another object of my invention is to provide a contact member so shaped that any arc formed thereat will be kept as far as possible from an adjacent body of electric insulating material.

Another object of my invention is to provide a 20 contact member adapted to be associated with a body of electric insulating material, which contact member will lessen the possibility of injury to neighboring parts by an arc which might be formed at the contact member.

25 In the drawing:

Figure 1 is a view in section through a device comprising a contact member embodying my invention.

Figure 2 is a fragmentary view, partly in section, of a modified form of contact member embodying my invention, and

Figure 3 is a view of a contact member embodying my invention mounted on a plug fuse, which is associated with a fuse holder assembly.

35 Referring first to Figure 1 of the drawing, I have there shown the contact member embodying my invention as operatively associated with a plug fuse holder assembly.

The assembly in this figure is shown as comprising a base 11 which includes a center contact member 13 and a screw shell contact 15. A fuse holder 17 is adapted to be associated with the base and comprises a screw shell 19 having positioned therein a tubular body of electric insulating material 21 which may be provided with internal screw threads 23 for the purpose of associating therewith any one of a number of different forms of electric circuit protective devices including a plug fuse body many kinds of which are well known in the art. The holder 17 includes also a bottom closure 25 of electric insulating material having an opening 27 therein, as well as a spring disc 29 on which is mounted a contact member 31, which contact member embodies my invention.

It will be noted that the contact member 31 comprises a main body portion 33 and an end portion 35 which is of substantially frusto-conical shape, the diameters of the end portion 35 decreasing with increase of the distances of such portions away from the body portion 31. The end contact surface 37 of the frusto-conical portion 35 is flat and is adapted to make abutting contact with the cooperating contact member 13. It is here pointed out that the diameter of the 10 body portion 33 of the contact member 31 is only slightly less than the diameter of the opening 27 and further that as a protective electric device embodying a plug fuse body is screwed into the tubular member 21, a center contact on the protective device will engage one end of contact member 31 and cause it to move downwardly (as seen in Figure 1 of the drawing) until the end contact surface 37 engages the cooperating contact member 13.

20 Referring now to Figure 2 of the drawing, I have there illustrated a somewhat different form of contact member 39, here shown as including a main body portion 41 of a diameter but slightly smaller than the diameter of the opening 27, and an end contact portion 43 the diameter of which is substantially constant and appreciably less than that of the body portion 41.

25 In Figure 3 I have shown a contact embodying my invention associated with a plug fuse. This fuse has a body of insulating material 51 adapted to make screw threaded engagement with threads 23 of the fuse holder. A flexible disc 53 corresponds to the flexible disc 29 of Figure 1 and has an aperture 55 through which may be passed the contact member 57 having a body portion 59 corresponding to the body portion 33, and an end portion 61 and end contact surface 63 corresponding to 35 and 37 respectively of Figure 1.

30 While it is not normally intended that the circuit including the cooperating contact members 13 and 31 or 57 is to be opened by unscrewing a fuse plug from the holder and thereby causing a slow separating movement of the contact member 31 or 57 from the contact member 13, it 40 is possible that this may be done and if this happens while a current is traversing this circuit, an arc will usually result. It is obvious first of all that any arc which may occur between the 45 end contact surface 37 or 63 of the member 31 or 57 and the contact member 13 will probably start at the contact surface 37 or 63 and will therefore be positioned a relatively large distance away 50 from the wall of the opening, which wall is, as 55

has already been stated, of electric insulating material.

I have found in those cases where the member 25 and the member 21 are made of molded composition, that while this material is electric insulating at ordinary temperatures, it may lose its electric insulating characteristics at higher temperatures and especially so when subjected to the influence of an electric arc. I have found also that since molded composition comprises an organic constituent there is a possibility of a vapor being given off by the material at high temperatures, which vapor under the influence of an arc may act as a conductor to increase the length of the arc or prolong the duration thereof.

It is obvious that an arc formed between the cooperating contact members 13 and 31 or 51 will be formed substantially within or not outside the periphery of the end contact surface 37 or 63, and that the slope of the sides of the portions 35 and 61 of the contact members will tend to keep the arc within these bounds as the distance from contact 13 to any point on the sides of contact portions 35 and 61 farther from the axis of the contact member will be greater than the distance to any point on the contact surface.

For similar reasons the shape of the contact member shown in Figure 2 tends to confine an arc which may be formed to the end of the portion of smaller diameter 43 which portion because of the larger diameter of the main body portion 41 is kept away from the walls of the opening 27 during the entire separating movement of the cooperating contact members.

The electric insulating material surrounding or encircling the contact member 31, 41 or 51 may also be of a kind which, when subjected to the influence of an arc, becomes electric conducting or heat carbonized and after the arc strikes or engages this material, it may be prolonged as to duration or increased as to its length and may therefore cause substantial injury to the electric insulating material. The contact members embodying my invention tend to keep any arc which may be formed between the separating contact members away from the electric insulating material and therefore greatly reduce the possibility of damage to the electric insulating material.

It will be obvious that the mass of my improved contact being greater at the end remote from the arcing surface will result in a tendency to cool any arc which may be formed thereat and this provides an advantage in addition to those provided by the contour of the contact member.

While I have mentioned "Bakelite" as one material with which the contact member embodying my invention may be associated, I do not desire to be limited thereto but may use my invention with any kind of molded insulating material.

While I have illustrated and described certain embodiments of devices embodying my invention, I do not desire to be limited thereto, but desire that the appended claims shall be so construed as to cover all devices coming within the scope thereof, which scope is to be limited by the prior art only.

I claim as my invention:

70. 1. An electrical contact member adapted to be movably fitted in an opening of a body of organic insulation material, said contact member comprising a main portion and a lesser portion with the contact face thereon, the main portion 75 having a substantial mass to absorb heat and

being adapted to fit closely yet movably in the entrance of the opening; the smaller portion being of substantially less mass and cross-sectional area and of such restricted length that a substantial amount of the heat generated therein 5 will be absorbed by the main portion; the smaller portion having such reduced cross-sectional area as to leave such an enlarged space between the contact face and the walls of the opening that an arc which may be formed at the contact 10 face will not extend to said walls to injure same.

2. An electrical contact member adapted to be movably fitted in an opening of a body of insulation material, the walls of the opening being subject to carbonization by an electric arc, said 15 contact member comprising a main portion and a lesser portion with the contact face thereon; the main portion having a substantial mass to absorb heat and being adapted to fit closely yet movably in the entrance of the opening; the 20 smaller portion being of substantially less mass and cross-sectional area and of such restricted length that a substantial amount of the heat generated therein will be absorbed by the main portion; the smaller portion having such reduced 25 cross-sectional area as to leave such an enlarged space between the contact face and the walls of the opening that an arc which may be formed at the contact face normally will not extend to said walls to injure same.

3. The combination of an electric contact member and a body of insulation material having an opening therein; the walls of said opening being subject to carbonization by an electric arc, said contact member comprising a main 35 portion of substantial mass to absorb heat, and adapted to fit closely yet movably in the entrance of said opening and a lesser portion with the contact face at the end thereof, of smaller mass, having such a restricted length that a 40 substantial amount of the heat generated therein will be absorbed by the main portion, the spacial relation between the lesser portion adjacent the contact face and the walls of the opening being such that an arc which may be formed 45 at the contact face normally will not extend to said walls to injure same.

4. An electrical contact member for a plug fuse adapted to be removably fitted in an opening of a body of organic insulation material, said 50 contact member comprising a main portion and a lesser portion with the contact face thereon, the main portion having a substantial mass to absorb heat and being adapted to fit closely yet movably in the entrance of the opening; the 55 smaller portion being of substantially less mass and cross-sectional area and of such restricted length that a substantial amount of the heat generated therein will be absorbed by the main portion; the smaller portion having such reduced cross-sectional area as to leave such an enlarged space between the contact face and the walls of the opening that an arc which may be formed at the contact face will not extend to said walls to injure same.

5. An electrical contact member for a plug fuse adapted to be removably fitted in an opening of a body of insulation material, the walls of the opening being subject to carbonization by an electric arc, said contact member comprising a main 70 portion and a lesser portion with the contact face thereon; the main portion having a substantial mass to absorb heat and being adapted to fit closely yet movably in the entrance of the opening; the smaller portion being

- of substantially less mass and cross-sectional area and of such restricted length that a substantial amount of the heat generated therein will be absorbed by the main portion; the smaller portion having such reduced cross-sectional area as to leave such an enlarged space between the contact face and the walls of the opening that an arc which may be formed at the contact face normally will not extend to said walls to injure same.
5. An electrical contact member for a plug fuse holder adapted to be movably fitted in an opening of a body of organic insulation material, said contact member comprising a main portion and a lesser portion with the contact face thereon, the main portion having a substantial mass to absorb heat and being adapted to fit closely yet movably in the entrance of the opening; the smaller portion being of substantially less mass and cross-sectional area and of such restricted length that a substantial amount of the heat generated therein will be absorbed by the main portion; the smaller portion having such reduced cross-sectional area as to leave 10 such an enlarged space between the contact face and the walls of the opening that an arc which may be formed at the contact face normally will not extend to said walls to injure same.
6. An electrical contact member for a plug fuse holder adapted to be movably fitted in an opening of a body of organic insulation material, said contact member comprising a main portion and a lesser portion with the contact face thereon; the main portion having a substantial mass to absorb heat and being adapted to fit closely yet movably in the entrance of the opening; the smaller portion being of substantially less mass and cross-sectional area and of such restricted length that a 15 substantial amount of the heat generated therein will be absorbed by the main portion; the smaller portion having such reduced cross-sectional area as to leave such an enlarged space between the contact face and the walls of the opening that an arc which may be formed at the contact face normally will not extend to said walls to injure same.
15. An electrical contact member for a plug fuse holder adapted to be movably fitted in an opening of a body of insulation material, the walls of the opening being subject to carbonization by an electric arc, said contact member comprising a main portion and a lesser portion with the contact face thereon; the main portion having a substantial mass to absorb heat and being adapted to fit closely yet movably in the entrance of the opening; the smaller portion being of substantially less mass and cross-sectional area and of such restricted length that a 20 substantial amount of the heat generated therein will be absorbed by the main portion; the smaller portion having such reduced cross-sectional area as to leave such an enlarged space between the contact face and the walls of the opening that an arc which may be formed at the contact face normally will not extend to said walls to injure same.
